UNITED STATES PATENT OFFICE.

LEONARD CLAYTON RIDGE, OF TORONTO, ONTARIO, CANADA.

FILING APPARATUS.

Application filed March 1, 1924. Serial No. 696,186.

The invention relates to improvements in filing apparatus as described in the present specification and illustrated in the accompanying drawings that form a part of the 5 same.

The invention consists essentially of the novel construction of the pockets or folders and constitutes an improvement on my prior Patent Number 1,468,213 granted on September 18th, 1923 for improvements in filing 10 apparatus.

One object of the invention is to provide means for accommodating matter to be filed, which is especially adapted for use with the 15 arrangement shown in my said former patent and which at the same time may be adapted for use with other supporting means.

Another object is to provide for the special 20 requirements in respect to the filing of various articles such as phonograph records, letters, folded documents and other matter.

A still further object is to provide a continuous series of pockets or folders adapted 25 to function without the employment of suspension means.

And generally the objects of the invention 30 are to provide filing apparatus which will be inexpensive to manufacture, simple to install, efficient in operation and durable.

In the drawings Figure 1 is a perspective view showing the filing apparatus in position in a drawer, portions of each being broken away to clearly disclose the construction.

35 Figure 2 is an end elevation of a portion of the continuous series of pockets shown in Figure 1, the bottom of the filing drawer and the lateral supports for the pockets being shown in section.

40 Like numerals of reference indicate corresponding parts in the various figures.

Referring to the drawings 1 is a drawer comprising a bottom 1^a, and walls 2 and 3 and side walls 4.

45 5 are trackways adapted to support the bars 6 which are transversely arranged in relation thereto and are provided with suitable means to permit of their being moved on said trackways towards and away from 50 one another, the construction of said trackways and of said supports or riders being described and claimed in my said former patent and not constituting features of the present invention.

55 The pockets 7 are constructed of inflexible material and rest on the drawer bottom

without the necessity of being suspended from the riders 6 as is necessary in the case of the folders described in my said former patent. Said pockets may be constructed independently of one another but it is preferable that they either be formed in continuous series as shown by simply folding or crimping transversely an elongated strip of material to extend over the rider 6 respectively and to provide V-shaped files therebetween, or formed of separate pieces folded and having the adjoining edges of adjacent files secured together above the corresponding riders; the walls of said pockets in any case being of considerably greater height than the distance between the tops of the riders and the drawer bottom so as to leave the pockets entirely free of engagement with the riders and thus permit of the proper coordination of the pockets and riders during the opening or closing operations.

The pockets 7 may be scored transversely as at 8 if desirable to permit of expansion and if considered necessary the under sides 80 of the bottoms or scored portions may be reinforced with linen or other suitable material.

As the walls of the pockets are constructed of inflexible material it is apparent that 85 said pockets will only accommodate contents of a thickness equal to the width of the scored portion expanded and as a consequence an increase in the amount of contents will simply tend to spread the bottom of the 90 pocket and draw downwardly on the walls thereof, but as the total depth of said walls is greater than the height of the riders from the bottom of the drawer said pockets will not at any time be suspended from said 95 riders.

In the event, however, of a pocket being forced in a lateral direction, as when the drawer is opened violently, the adjacent riders 6 will arrest the lateral movement of 100 said pocket and constitute a lateral support therefor.

What I claim is:

1. In filing apparatus, in combination, a drawer, a member folded transversely at intervals throughout its length to form vertical V shaped pockets having inflexible walls, adapted to rest on the drawer bottom, said walls being scored transversely to permit of the bottom of said pockets respectively 105 being spread by the contents thereof, and transverse bars positioned between adjacent 110

- pockets intermediate of the height thereof and constituting lateral supports therefor, said bars being mounted for movement longitudinally of said drawer.
5. 2. In filing apparatus, in combination, a drawer, a member folded transversely at intervals throughout its length to form vertical V shaped pockets having inflexible walls adapted to rest on the drawer bottom, said 10 walls being scored transversely to permit of the bottom of said pockets respectively being spread by the contents thereof, and transversely arranged longitudinally movable bars positioned between said pockets 15 respectively, said bars being positioned on a lower plane than the tops of said pockets and constituting lateral supports for said pockets.
3. In filing apparatus, the combination of 20 a drawer, bars extending transversely of

said drawer and slideable longitudinally thereof, and integral V shaped pockets positioned between adjacent bars respectively and standing on the drawer bottom permanently free of suspension from said bars. 25

4. In filing apparatus, the combination of a drawer, a plurality of integral parallel transverse pockets adapted to stand on the bottom of said drawer and being capable of spreading movement longitudinally of said 30 drawer, the walls of said pockets being scored to permit of the expansion of the bottoms thereof, and transversely arranged laterally movable bars positioned within said drawer between the respective pockets and constituting lateral supports only therefor. 35

Signed at the city of Toronto, Ont., this fifth day of February, 1924.

LEONARD CLAYTON RIDGE.
